UNITED STATES PATENT OFFICE.

FREDERICK W. BRITTIN, OF BIRMINGHAM, CONNECTICUT, ASSIGNOR TO THE
SILVER PLATE CUTLERY COMPANY, OF SAME PLACE.

DESIGN FOR A FRUIT OR TABLE KNIFE.

SPECIFICATION forming part of Design No. 16,721, dated June 8, 1886.

Application filed March 29, 1886. Serial No. 197,042. Term of patent 3½ years.

To all whom it may concern:

Be it known that I, FREDERICK W. BRITTIN, a citizen of the United States, residing at Birmingham, in the county of New Haven and State of Connecticut, have invented and produced a new and original Design for Fruit or Table Knives, of which the following is a specification, reference being had thereto to the accompanying drawings.

Figure 1 is an elevation, and Fig. 2 a plan view, of my newly-designed fruit or table knife. The blade, bolster, and handle are in a single piece.

The leading features of my design consist in a cylindrical handle having a bulb or ball at its outer end, a bolster tapering outward slightly toward the blade, and a slightly curved blade.

A is the handle; B, the bulb or ball at its outer end; C, the bolster, which is connected to the handle by a shoulder, D, and tapers outward slightly toward the blade; and E, the

blade, which curves slightly downward, then upward, and at its outer end is beveled backward from the cutting-edge to the back of the 25 blade. The handle may be ornamented in any suitable manner. This, however, forms no part of my present invention.

I claim--

The design for fruit or table knives herein 25 shown and described, the same consisting of a cylindrical handle having a bulb or ball, B, at its outer end, a bolster, C, smaller than the handle, to which it is connected by a shoulder, D, and which tapers outward slightly and extends into a blade, E, the latter being curved 35 slightly downward, then upward.

In testimony whereof I affix my signature in presence of two witnesses.

FREDERICK W. BRITTIN.
